HARRY E. CAMPBELL, OF BALTIMORE, MARYLAND, ASSIGNOR TO CAMPBELL METAL
WINDOW CORPORATION, OF BALTIMORE, MARYLAND, A CORPORATION OF MARY-
LAND

WINDOW SILL AND SASH CONSTRUCTION

Application filed July 2, 1929. Serial No. 375,384.

This invention relates to a particular construction for making a tight joint between the sash and frame of a window adjacent the sill, and contains matter derived from my earlier application Ser. No. 165,526, filed Feb. 3, 1927, and Ser. No. 295,085, filed July 24, 1928.

According to the present invention, I am able to make a very efficient joint between the sill and the sash in a window of the type comprising jambs having a vertical opening in their inner walls to receive the lower sash and enlarged chambers back of such opening. In a window of this construction it is highly desirable that the lower sash be pressed outward so that it will make a tight joint with the parting strip or baffle which provides the outer edge of the vertical opening in which the sash moves. In previous constructions with windows of this type there has been a compromise along the sill where the sash was forced inward to form a tight joint along the sill line but left a space for air leakage on the outside between the sash and baffle. I have found that this can be overcome by providing a spring member which is adapted to push the sash outward against the baffle but will exert pressure for substantially the width of the sash between the fixed sill portions and the sash. Such spring member may be attached to the sill but I prefer to attach it to the sash.

My invention may be readily understood by reference to the accompanying drawings in which Fig. 1 is a sectional view through the sill and sash showing a portion of the jamb face and Fig. 2 is a section on line 2—2 of Fig. 1 but with the sash raised so that it does not show in this figure.

In these drawings the jamb construction is similar to that shown in my earlier Patent No. 1,549,711, issued August 11, 1925, and the manner in which the sill and jamb are connected together is as shown in that patent, though the sill is slightly modified.

In the illustrative example the lower sash has a bottom plate 10 bent outwardly and again upwardly, as indicated at 12, to form a glass rabbet. Plate 10 is adapted to extend down to meet the sill 14 which has a horizon-

tal portion 16, a portion 18 bent down and inwardly and an outwardly extending portion 20. Welded on the outside of the plate 10 is a stop 22 which locks in place a weather seal 24 which is bent around the lower part 55 of the plate 10 and is adapted to make spring contact with the corner 17, formed by the meeting of portions 16 and 18 of the sill. The position which the upper central portion of the stop 24 will assume relative to the plate 10 when the lower sash is raised, is indicated by broken lines in Fig. 1.

In the construction here illustrated, the sill 14 extends beyond the inner face of the jamb walls at least as far as partition member 25, and plate 10 extends practically to the partition member, as indicated in broken lines in Fig. 2. Member 24 is preferably made the same length as plate 10. The inner jamb wall is formed in three parts. The portion 26 lies above the horizontal portion 16 of the sill and has its lower corner cut off as indicated at 28 to permit of movement of the upper edge of weather stop 24. The parting strip or baffle 30 is positioned away 75 from portion 26 far enough to form a slot 32, and the balance of the inner jamb wall is formed by plate 34 (which is here shown as integral with partition 25), leaving a slot 36 between it and the parting strip 30. As shown in Fig. 2, there are enlarged chambers back of slots 32 and 36. The member 38 is welded on the plate 10 to form a glass channel 40. This channel is slightly wider than the thickness of glass to be used but is partly filled by the hook-shaped member 42 which contacts with the horizontal portion 16 of the sill, and is held in place by screws not here shown.

By this arrangement an efficient joint between the sill and sash is formed which extends into the jamb to the point where the sash makes rubbing contact with a partition member in the jamb so that there is substantially no chance for leakage at the 95 corners of the sash. At the same time the lower sash is under spring tension forcing it out against the parting strip or baffle.

What I claim is:

1. In a window of the type having jambs, 100

- openings through the inner walls of the jambs, a parting strip forming part of the inner jamb wall between such openings, separate enlarged chambers back of such openings and sashes having plates adapted to extend through such openings, a sill having an approximately horizontal portion extending inside of the lower sash, a portion below such horizontal portion extending outside of the lower sash and a connecting portion between said two portions, a member on the sash adapted to contact with said horizontal portion that extends inside of the sash, and spring means interposed between the lower sash and said connecting portion of the sill adapted to push the lower edge of the lower sash away from said connecting portion and hold the sides of such sash against the parting strip.
2. A structure as specified in claim 1 in which said spring means extends substantially the length of the lower sash and enters said jambs so that the same serves as an auxiliary sealing mechanism for the lower sash.

3. In a window of the type having jambs, openings through the inner walls of the jambs, a parting strip forming part of the inner jamb wall between such openings and separate enlarged chambers back of such openings, a sill having an offset portion with its edge approximately aligned with the indoors side of the opening for the lower sash, a lower sash having plates extending through the indoors pair of said openings and a lower portion adapted to extend down below the edge of the offset portion of the sill, and spring means for exerting pressure between the offset portion of the sill and said lower portion of the lower sash.

4. A structure as specified in claim 3, in which such spring means is carried by the lower sash and is adapted to exert pressure against the edge of such offset portion for substantially the width of the lower sash.

5. A window construction comprising jambs having vertical openings in their inner walls to receive the lower sash, enlarged chambers back of such openings, a sill connecting the jambs having an offset portion with its edge approximately in line with the room side of such vertical openings and extending into said enlarged chambers, a lower sash having portions adapted to enter said openings and a flexible spring member carried by the bottom rail of the lower sash adapted to contact with the offset portion of the sill for substantially the full width of the sash, said vertical openings being enlarged immediately above the sill to permit such flexible member to contact freely with the sill.
